United States Patent Office.

GEORGE W. FRY, OF PITTSBURG, PENNSYLVANIA.

Design No. 3,380, dated February 16, 1869.

DESIGN FOR A LAMP-CHIMNEY.

The Schedule referred to in these Letters Patent and making part of the same.

To all whom it may concern:

Be it known that I, GEORGE W. FRY, of Pittsburgh, in the county of Allegheny, and State of Pennsylvania, have invented and designed a new Pattern and Form of Lamp-Chimneys; and I do hereby declare that the following is a full, clear, and exact description of the same, reference being had to the annexed drawing, making a part of this specification.

Figure 1 of the drawings is a representation of an external view of the broad side of my lamp-chimney, and

Figures 2 and 3 are external views of the narrow side of the same.

What I claim as my invention, and desire to secure by Letters Patent, is—

The design for lamp-chimneys herein described and set forth.

In testimony that I claim the above, I have hereunto subscribed my name, in the presence of two witnesses.

GEORGE W. FRY.

Witnesses:

JOHN I. STEEN,
LEONARD S. JOHNS.
